[57] CLAIM

The ornamental design for a "compact disc holder", as shown and described.

DESCRIPTION

FIG. 1 is a top right side perspective view of a "compact disc holder" showing my new design, the left top side perspective view being identical thereto with compact discs shown in phantom;

FIG. 2 is a bottom left side perspective view;

FIG. 3 is a right side elevational view thereof, the left side elevational view being identical thereto;

FIG. 4 is a front elevational view thereof, the rear elevational view being identical thereto, and,

FIG. 5 is a top plan view thereof, the bottom plan view being identical thereto.

The broken line showings of compact discs in FIG. 1 are for illustrative purposes only and form no part of the claimed design.
